UNITED STATES PATENT OFFICE.

JAMES H. DWIGHT, OF ATLANTA, GEORGIA.

COTTON-CHOPPER.

1,284,075.

Specification of Letters Patent.

Patented Nov. 5, 1918.

Application filed March 12, 1918. Serial No. 221,900.

To all whom it may concern:

Be it known that I, JAMES H. DWIGHT, a citizen of the United States, and a resident of Atlanta, in the county of Fulton and State of Georgia, have invented a new and Improved Cotton-Chopper, of which the following is a full, clear, and exact description.

My invention relates to implements for chopping out surplus cotton plants, and more particularly the invention relates to an apparatus for the indicated purpose, in which rotary chopping elements are arranged to turn about a vertical axis, and to have an up-and-down movement to give the chopping action. The up-and-down movement is produced by a sinuous track, on which the arms supporting the chopper blades travel. The said arms are pivoted to have a vertical rocking movement in response to the sinuosities in the track. The rotary movement of the chopper elements is effected through the medium of gearing driven from the axle of the running wheels. I employ a harrow at the front arranged to be adjusted laterally, and cultivator shovels at the rear of the chopper,

The invention will be particularly explained in the specific description following.

Reference is to be had to the accompanying drawings forming a part of this specification, in which similar characters of reference indicate corresponding parts in all the views.

Figure 1 is a side elevation of a cotton chopper embodying my invention;

Fig. 2 is a plan view thereof;

Fig. 3 is a longitudinal vertical section;

Fig. 4 is a detail sectional plan view showing the rotary choppers and their supporting tracks;

Fig. 5 is a perspective view of the sinuous track.

In constructing the illustrated embodiment of the invention, a frame 10 is provided, formed of metal elements. The frame as illustrated comprises side bars extending inwardly toward each other at the front, as at 10^a, and then, forwardly, the forwardly extending ends 10^b being secured by bolts 11, or equivalent means, to a tongue member 12. The tongue 12 has provision for receiving a clevis or other draft connection, there being illustrated a transverse hole 13 for the purpose. The frame includes also a front cross bar 14, having a central forward extension

15, to which the rear end of the tongue 12 is secured by a bolt 16 or the like.

Supported on the front cross bar 14 is a block 17, which forms a bearing for a vertical spindle 18. On the lower end of the spindle is secured a track 19, hereinafter referred to. The connection with the track 19 and the spindle 18 may be produced by arms 20 which extend outwardly and upwardly from a head or enlargement 21 on the lower end of the spindle. Chopping blades 22 are carried by the depending ends of arms 23 provided with rollers 24 that travel on the track 19. The arms 23 are received in sockets 25 in yokes 26, there being two yokes, each carrying two chopping blades at diametrically opposite points. The sockets 25 are provided with set screws 27 to hold the arms in position and permit radial adjustment thereof. Each yoke 26 comprises a pair of arms extending at opposite sides of the spindle 18, and the arms of each yoke are provided with set screws 28 which bind against a sleeve 29, which is loose on the spindle 18. The said screws 28 thus form centers or pivots permitting a vertical rocking movement of the yokes 26 and the chopping blades carried thereby. To prevent turning of the screws 28 a pin or cotter may be inserted in a hole in each screw as indicated at 28^a, Fig. 3.

In order to give rotary movement to the sleeve 29, for revolving the chopper blades, driving connection is established between said sleeve and the vehicle axle 30 mounting the running wheels 31. The driving connections may consist of a bevel gear 32 on the sleeve 29, meshing with which is a bevel gear 33 on a horizontal shaft 34. The said shaft 34 has a bearing at its front end in the block 17, and near its rear end has a bearing in a frame bar 35. On the rear end of the shaft 34 is a bevel gear 36, which meshes with a similar gear 37 on the axle 30.

In order to throw the gear 33 out of driving connection with the gear 32, said gear 33 is slidable on the shaft 34 and may be shifted through the medium of a pedal 38. The pedal 38 is pivoted, as at 39, on a lug 40 or equivalent fixed member; as shown, the said lug 40 is on the platform carrying the driver's seat 42. The pedal 38 terminates at its lower end in a fork that engages a collar 43 on the gear 33 as is usual with similar de-

vices, so that a movement of the pedal may be caused to give a rearward sliding movement to the gear wheel 33 against the action of a compression spring 44. The spring 44 tends to maintain the gears 32, 33, in mesh. Said spring encircles the shaft 34, and abuts at its ends respectively against the bearing bar 35 and against the hub of the bevel gear 33.

10 The endless track 19 is generally of circular form as viewed in plan, and at the rear end is formed with a rise or arch 19^a. At the front, diametrically opposite the rise 19^a, the track is depressed as at 19^b. Inasmuch as the blades 22 are pivotally supported for vertical rocking through the medium of their carrying yokes 26 and the pivots provided by the set screws 28, the yokes will accommodate themselves to the elevated and 20 depressed portions of the track, so that the blades in rotating, will give a downward sweep to effect the chopping action as each blade reaches the front of the track. As the blades reach the rear of the track they will 25 be lifted and clear the row of plants.

I provide a harrow at the front of the implement. As best shown in Fig. 2, the harrow comprises opposite main side bars 45 oblique to each other and to the tongue 12, 30 and pivotally supported by bolts 46 (Fig. 3) on a depending hanger 47, which is secured to the tongue 12. Additional bars 48, 49, are disposed between and rearward of the outer harrow bars 45 and are arranged after the 35 manner of toggle members. The bars 48 are pivoted at 50 to the main bars 45, and are pivoted to each other, as at 51 at their crossing points. Similarly the bars 49 are pivoted to the bars 48, as at 52, and are pivotally connected to each other at their crossing points as at 53. The bars 49 are suspended from the tongue 12 by additional hangers 47^a. The hangers 47, 47^a, are secured to the tongue 12 by bolts 47^b which may be passed 45 through any one of a vertical series of holes 47^c in said hangers. Each of the bars 48 is bent downwardly and forwardly to provide harrow teeth 54. The several pivotal connections between the harrow bars are effected 50 through the medium of bolts, as clearly seen in Fig. 3, and the construction is such that the harrow may be contracted or expanded laterally.

Cultivator shovels 55 are mounted in the 55 rear of the chopper blades. The said shovels are carried by beams 56 and these beams are slidable on bars 57, being fitted to the latter by sleeves 58 that slide on the said bars 57, the forward ends of the beams 56 being pivoted to the sleeves by screw studs 59 and nuts 60, or equivalent means. At the rear ends the beams 56 are hung on crank shafts 61, which rock at their outer ends in bearings 62 on the side bars 10, and at their inner 60 ends in bearing 63, which are mounted on

the rear cross bar 64 of the frame. The cross bar 64 has depressions 65 adjacent to the crank shafts 61 to accommodate the beams 56. The cultivator beams 56 are centered on the crank shafts 61 by means of collars 66 and set screws 67 that secure the collars in fixed position at any desired point.

In order to rock either crank shaft 61 to raise or lower either cultivator shovel 55, a hand lever 68 is provided on each crank shaft 75 and equipped with the usual latch 69 to engage a curved rack 70.

I provide means whereby to raise or lower the track 19 and thereby raise or lower the chopper blades 22. As one example of means 80 for the purpose, I have shown a nut 71 which is threaded onto the upper end of the spindle 18, the said nut bearing against the upper end of the block 17.

In the raising or lowering of the track, 85 the chopper blades also will be raised and lowered and in order that the raising of the blades will not strain the track, the sleeve 29 to which the yokes carrying the chopper blades are pivoted, is made to rest 90 at its lower end against the head or collar 21 on the spindle 18. The upper end of the sleeve 29, when the latter is raised, is accommodated in an annular recess 72, in the under side of the block 17. The sleeve 95 29 is permitted a sliding movement through the bevel gear 32, the latter being splined to the sleeve as at 73. The sleeve 29 may have a sliding movement also through a collar 74, which in the present example is 100 hung from the front cross bar 14, or other member of the frame, by a hanger member 75 integral with said collar.

It will be understood that any other suitable means may be employed for permitting 105 the vertical movement of the track and chopper blades in response to an upward movement of the spindle 18. The pivots provided by the set screws 28, for instance, constitute a means to vertically adjust the 110 yokes on the sleeves separately from the vertical adjustment of the spindle and track instead of simultaneously raising and lowering the yokes and track.

I would state in conclusion that while the 115 illustrated example constitutes a practical embodiment of my invention, I do not limit myself strictly to the mechanical details herein illustrated, since manifestly the same can be considerably varied without departure from the spirit of the invention as defined in the appended claims.

Having thus described my invention I claim as new and desire to secure by Letters Patent:

1. In an apparatus of the character described, a member mounted to turn about a vertical axis and pivoted to rock in a vertical plane, a chopper element on said member, actuating means for said member, and 130

a track on which said member travels, said track having a depression therein to permit a downward movement of the said element in chopping.

5. 2. In an apparatus of the character described, a yoke mounted to turn about a vertical axis and pivoted between its ends for up-and-down rocking movement, arms carried by the yoke at opposite sides of its 10 axis, chopper blades on said arms, rollers on the arms, a track on which the rollers travel, said track presenting a depression and an opposed elevation to tilt said yoke on its pivots, and means for actuating the 15 yoke.

3. In an apparatus of the character described, a frame, a substantially vertical spindle on said frame, a loose sleeve on the 20 spindle, means for turning the sleeve, a track carried by the spindle, a yoke mounted to turn with the sleeve and pivoted with the latter to tilt vertically thereon, arms on the yoke having members resting on the track, said track having sinuosities to tilt 25 the yoke as it turns, chopping blades on said arms, and means to raise and lower the spindle.

4. In an apparatus of the character described, a frame, a substantially vertical spindle on said frame, a track on said spindle, a sleeve loose on the spindle, a chopper element pivoted on the sleeve to rock vertically and having members running on the 30 track, said track having a depression and an elevation to tilt the chopping element, a gear wheel on the sleeve, a horizontal shaft, a gear wheel slidable on said shaft into and out of engagement with the first 35

gear wheel, means for turning said shaft, a spring normally tending to maintain the 40 second gear wheel in mesh with the first gear wheel, and means for shifting the second gear wheel against the tension of the spring.

5. In an apparatus of the character described, a frame, a vertical spindle on said frame, a sleeve loose on the spindle, a track on the spindle, a chopping element pivotally mounted on the sleeve and engaging the track, said track having a depression 50 and an elevation to tilt the chopping element, means for actuating the sleeve, and means for vertically adjusting the spindle, the said sleeve being supported on said spindle to rise with the spindle when the latter 55 is raised.

6. In an apparatus of the character described, a frame, a vertical spindle on the frame, means for vertically adjusting the spindle, a track on the spindle having an 60 elevation and a depression, a sleeve loose on the spindle, a yoke carrying chopping elements at opposite sides of the sleeve and having members running on said track, set screws pivotally mounting the yoke on the 65 sleeve and constituting a means to vertically adjust the position of the yoke, and means for actuating the sleeve.

In testimony whereof I have signed my 70 name to the above specification in the presence of two subscribing witnesses.

JAMES H. DWIGHT.
